7 Claims. (Cl. 250—27)

In an amplifier arrangement with a plurality of amplifying tubes, in which all tubes amplify the same frequency band, for instance the intermediate frequency of a superheterodyne receiver, difficulties arise, as well known, by reason of undesirable reaction couplings. In addition to these known effects there appears a new group of disturbances if the amplifying tubes employed have a particularly large effective steepness

10 ($S \geq 5$ ma./volt).

In modern television art it is possible, on account of the absence of strong disturbances in the ultra-short wave band, to employ intermediate frequency amplifiers having a total amplification amounting to about ten times that possible in the case of sound reception on the medium wave band. It is necessary for the valves in such intermediate frequency amplifiers to have 15 very large slopes, as the effective anode resistances in the case of television are very much smaller than the resonance circuit resistances in the radio art (order of magnitude 5,000 ohms as compared with several hundred thousand ohms). Finally, with the object of preventing potential-overloading of the control grid of the television tube with its very harmful effects on the quality of the image, and also an inadmissibly high 20 amplification of the humming in the mains, a low-frequency amplification after the intermediate frequency rectifier is preferably dispensed with entirely. The intermediate frequency amplifier alone must accordingly cope with the whole reception amplification, and 25 possess a degree of amplification which is greater than 500,000.

There then occur in practice, in the performance of these constructions, the stated interfering oscillations and self-exitations partly in 30 unusual form, which call for a particular remedy forming the subject matter of the present application.

According to the main object of the invention, in an amplifier arrangement with several amplifier tubes for producing very high amplification over a frequency band separate high frequency filters are used in the anode-, grid- and screen-grid branches of each amplifying stage containing decoupling condensers connected directly with the cathode of the corresponding tube, each cathode connected directly with the earthing point by additional earthing condensers.

A description will now be given, by way of example only, of an embodiment of the invention, 55 reference being made to the drawings wherein

Fig. 1 shows the circuit of a portion of an intermediate frequency amplifier of a superheterodyne receiver,

Fig. 2 shows the construction of a coupling device,

Fig. 3 shows the construction of another coupling device and

Fig. 3a shows the circuit of the mixing tube which precedes the intermediate frequency 10 amplifier of Fig. 1.

Fig. 4 shows the method of connecting together the heating leads of the oscillating and amplifying stages in a superheterodyne circuit.

In Fig. 1 there is illustrated a group of two amplifying tubes 1 and 2, such as are used in the intermediate frequency amplifier of a television superheterodyne, and of which each single tube is furnished with a steepness of approximately 6 milliamperes per volt, or more, and permits of an amplification of approximately 25 20 per stage. For each stage filters are arranged in the anode circuit, screen-grid circuit and control-grid circuit consisting of filter resistance in these leadings and by-passing decoupling condensers.

It has been found that the decoupling condensers, which in Fig. 1 are designated 3, 4 and 5 for the control grid circuit, anode circuit and screening-grid circuit should not be connected in the well known manner with the metallic receiver chassis 6, the earth or mass, but in accordance 30 with the invention may be connected directly with the cathode of each corresponding stage. It is convenient and advantageous to combine the three or more blocking condensers aforesaid to form a common combination condenser, which is 35 arranged in a uniform metallic casing cup.

Elimination of the self-excitation otherwise occurring very strongly is not performed alone by this combination of the short-circuit condensers 3, 4, 5 in groups. According to the invention, the cathodes of all single amplifying stages must be connected separately with the earthing point 6, each through the medium of a high-frequency earthing condenser 7, whereby the metallic receiver chassis may be selected as 45 earthing point, and preferably the connecting point of the condenser 7 should be in the vicinity of the appertaining tube base, in which connection, however, the connection point should not be situated in the vicinity of parts of the chassis 50 traversed by eddy currents.

According to the invention, the supply of the direct currents from the negative pole of the anode-current source is performed through the medium of chokes 8, and the path over these 55

- chokes must remain the only path of access in respect of the anode current. The natural wave of the chokes 8 is, in accordance with the invention, selected to be smaller than the amplifier 5 wave lengths in operation, so that the chokes 8, despite the presence of unavoidable parallel building-up capacities, always possess an inductive resistance character. In practice an order of magnitude of .1 mf. has been found to be 10 sufficient and very effective for the condenser 7, and 40 windings on a cylinder having a diameter of 20 mm. for the chokes 8. The leads for the grid bias 9 and the anode potential 10 may be disposed as desired, and no longer represent 15 sources of error if the high ohmic series resistance of the grids 11 (approximately 50,000 ohms), the anode currents 12 (5,000 ohms) and the screening grids 13, 14 (each approximately 50,000 ohms) as indicated in Fig. 1 are connected in 20 the manner shown in the invention, i. e., in such fashion that the same are fully effective as blocking resistances in respect of the high-frequency currents traversing the condensers 3, 4, 5.
- With the heating of all stages of the tube from 25 the same heating transformer 15', as required in practice, the embodiment of the heating circuit will be as follows:
- According to the invention, there are provided 30 between each two branches which conduct the heating current from the two heating lines 15 and 16 to the single amplifier stages chokes 17, 18 of low ohmic resistance, and in addition the ends of the heating filament for each tube are earthed per se over a pair of earthing blocks 35 condensers 19, 20. This method of heating, earthing and choke feeding in accordance with the invention is of particular importance in practice in the heating circuit of the local oscillator tube, which oscillates in the receiving apparatus 40 to an ultra-short wave. It has been found in practice that if the earthing blocks 19, 20 are not provided for this stage of the tube, or if they are not connected in the immediate vicinity of the ends of the heating filament, an exactly defined natural wave is capable of developing in 45 the heating circuit, in view of the frequency of which the reception may be interfered with or rendered impossible by the occurrence of an alien oscillation or an oscillation gap and the like.
- According, therefore, to the invention, the pair 50 of condensers 19, 20 and the pair of coils 17, 18 are employed under all circumstances for the heating circuit of the local oscillator tube; on the other hand this method may be adapted less frequently for the remaining amplifier stages, and in particular may be used for example only after each second amplifier stage (see Fig. 4).
- After complete de-coupling of interfering 55 oscillations in the heating circuit and in the circuits of the amplifying tubes there occurred in the practical operation also a third group of interfering oscillations, viz., ultra-frequent self-excitation of the anode circuits of the amplifying tubes 1, 2, etc. With the choke or transformer 60 amplification over inductances 21, 22, employed in the case of high-power television receivers there occurs with great certainty upon the combination of amplifying tubes with the stated particularly large steepness, self-excitation on 65 an ultra-short wave, the frequency of which is presumably determined by the stray inductance of the anode choke in combination with the anode operating capacity.
- In particular the existance of these oscillations 70 can be proved at the anode lead between the tube

anode and the anode choke. An oscillation of this nature interferes with normal reception by displacement of the working points, by abnormal anode currents, and by gaps and breaking points and the like when passing over the receiving wave 5 of equal frequency. The existance of oscillations of this character is frequently very difficult to determine. The connection in accordance with the invention of protective resistances 23 in the lead to the anode gap of the amplifying tube 10 has been found to be an effective remedy. The resistances 23 should be negligibly small in value compared with the operating impedances of the anode chokes 21 at the intermediate frequency (approximately 5,000 ohms), but on the other hand they should have sufficient effect on the disturbing frequency oscillation circuit formed by the operating capacity of the tube anode and the stray inductance of the coil, in such fashion that the oscillations are compelled to break off. A 500-ohm resistance which is so constructed as 15 to be free from inductance and low capacity e. g. a normal porcelain and graphite resistance rod, satisfies these requirements without appreciably 20 impairing the receptions.

Fig. 2 shows the manner in which this resistance rod was embodied mechanically, and in what manner the screening means require to be applied so that the resistance is not bridged by 25 capacities and thus made ineffective. The resistance rod 23 itself is soldered in mechanically 30 rigid fashion to the threaded eye 24. A small tube 25, which is not screened and consists of insulating material, acts as manipulating member 35 and carries at its end the screening sleeve 25', which is insulated against the anode line 27 for example by means of a rubber tubing 26 and is itself earthed (earth 6=receiver chassis). The screened cable should be as poor in capacity as 40 possible, so that the largest possible ratio

$$\frac{L}{C}$$

is obtained, and so that with the prescribed carrier frequency as many windings as possible may 45 be wound on the coupling transformer. In this way there is obtained an amplification increasing in proportion to the square of the windings and proportional to the ratio

$$\sqrt{\frac{L}{C}}$$

in the width of the band. It is only when observing the de-coupling measures set forth according to the invention and simultaneously employing all of the means described in accordance with the invention that it is possible to perform 55 absolutely stable amplification, for example of the 150-meter carrier wave with a width of band of ± 500 k. c., up to a total amplification of more 60 than 1,000,000.

In this way it is possible to supply mass-scale production amplifiers with amplification figures of this kind, and to increase in stable fashion the total amplification up to distinct predominance of the grain effect.

Beyond this, however, particular care is called for by the connection of the first stage, which is coupled in direct fashion with the ultra-short wave aerial.

Fig. 3a shows a circuit arrangement of the first valve 30 which is the mixing valve. The aerial 28 is connected by means of a very small capacity 29 with the cap of the input grid 34 on the head of the valve 30. This capacity 29 is 75

formed simply by a rod inserted in insulated fashion in a sleeve (see the corresponding parts 43 and 38 in Fig. 3) and amounts to $0.1 \cdot 10^{-5}$ microfarads. The circuit arrangement of the 5 first valve consists of a local-oscillator tube (type ACH 1, Telefunken), which with an ultra-short wave oscillatory circuit, the single tuning circuit 10 31, 32 operated by hand, produces in capacitative three-point connection local oscillations, and in a 15 hexode system provided in the tube in the intermediate frequency anode 33 passes the carrier wave to the described intermediate frequency amplifier. In this connection the receiving grid 34 is screened off as well as possible against the 20 oscillator vibration by means of a screening grid 35, and is conducted out of the top of the tube, whilst all remaining electrodes are passed out at the base of the tube at the bottom. The aerial input connection according to the invention 25 having an oscillation choke 36 and the very small aerial condenser 29 renders the use of a special tuning circuit for the aerial unnecessary. The aerial choke 36 can, however, build up a sufficiently high resistance in an additional frequency range only if the earth capacities in parallel therewith are made as small as possible. According, therefore, to the invention, the choke 36, which is illustrated by way of example in Fig. 3, is constructed as manipulating member. 30 For this purpose it is situated within an insulating tube 37, which carries a jacket sleeve 38 capable of being fitted on the tube cap 39. The screening means, which is required for the lead from the negative pole of a grid bias source of 35 potential, does not commence until after the coil, and is designated 40. The same may be constructed as capacity-loaded rubber cable, and made as long as desired. The sleeve 38, which conducts the bias 41 through the choke 36 to the 40 grid cap 39, is filled out in the interior with insulating material 42, which acts as dielectric for the plug pin 43. The latter is connected with the aerial 28. In order now that the lead 44 to the aerial, so far as the same is located within 45 the chassis of the apparatus, will not intercept any oscillations present in the apparatus, for example, the heterodyne oscillations, which would cause self-excitation or radiation, the lead 44 is screened off within apparatus by a screening jacket 45. This screening jacket, however, 50 in accordance with the invention, is selected to be very poor in capacity as compared with the core 44 (diameter ratio 1/10). In this manner a resonance aerial 28 may be utilized for obtaining 55 a potential bulge as large as possible at the point 43.

The measure set forth in Fig. 3 is naturally merely one of several possible constructions solving the problem recognized by the applicant and 60 consisting in making the capacity in parallel with the aerial choke 36 as small as possible and thus making the marginal width of the choke as large as possible, at the same time, however, completely screening off the aerial circuit 28 against the heterodyne oscillations, and also completely 65 screening off the grid 34 against a directly picking-up of waves in the case of absent aerial.

In Fig. 4 there is shown the special circuit connection of the heating leads in case of a superheterodyne circuit arrangement in which the 70 first stage is an oscillation stage which the following amplifier stages are oscillated to. In the lead line between the heating leads of the first oscillating stage and the associated amplifier 75 stage high frequency chokes 17 and 18 are ar-

ranged but between the first and second amplifier stage these chokes between the heating leads are missing and only after the second amplifier stage such chokes are used.

I claim:

1. In an amplifier system with several amplifier stages for obtaining very high amplifications, preferably for amplifying the intermediate frequency band of a television superheterodyne arrangement each of said amplifying stages containing an amplifier tube connected with an anode circuit, a screen grid circuit and a control grid circuit, separate high-frequency filters in said anode-circuit, in said screen-grid-circuit and in said control-grid-circuit of each of said 10 amplifier stages for avoiding disturbing coupling, said filters containing decoupling condensers connected directly with the cathode of the corresponding amplifier tube, each cathode connected directly with the earthing point by additional 15 earthing condensers.

2. In an amplifier system with several amplifier stages for obtaining very high amplifications, preferably for amplifying the intermediate frequency band of a television superheterodyne arrangement each of said amplifying stages containing an amplifier tube connected with an anode circuit, a screen grid circuit and a control grid circuit, separate high-frequency filters in said anode-circuit, in said screen-grid-circuit and in said control-grid-circuit of each of said 20 amplifier stages for avoiding disturbing coupling, said filters containing decoupling condensers connected directly with the cathode of the corresponding amplifier tube, each cathode connected directly with the earthing point by additional 25 earthing condensers, the cathode of each amplifier stage connected with the cathode of the following amplifier stage by a high-frequency choke, the impedance of said choke being purely 30 inductive for the frequency to be amplified and large as compared with the earthing resistance of said earthing condenser.

3. In an amplifier system with several amplifier stages for obtaining very high amplifications, 45 preferably for amplifying the intermediate frequency band of a television superheterodyne arrangement each of said amplifying stages containing an amplifier tube connected with an anode circuit, a screen grid circuit and a control grid circuit, separate high-frequency filters in said anode-circuit, in said screen-grid-circuit and in said control-grid-circuit of each of said 50 amplifier stages for avoiding disturbing coupling, said filters containing decoupling condensers connected directly with the cathode of the corresponding amplifier tube, each cathode connected directly with the earthing point by additional 55 earthing condensers, the cathode of each amplifier stage connected with the cathode of the following amplifier stage by a high-frequency choke, the impedance of said choke being purely 60 inductive for the frequency to be amplified, and large as compared with the earthing resistance of said earthing condenser, said anode-circuit filters containing additional small ohmic resistance for suppressing ultra-high-frequency oscillations.

4. In an amplifier system with several amplifier stages for obtaining very high amplifications, 70 preferably for amplifying the intermediate frequency band of a television superheterodyne arrangement each of said amplifying stages containing an amplifier tube connected with an anode circuit, a screen grid circuit and a control 75

- grid circuit, separate high-frequency filters in said anode-circuit, in said screen-grid-circuit and in said control-grid-circuit of each of said amplifier stages for avoiding disturbing coupling, 5 said filters containing decoupling condensers connected directly with the cathode of the corresponding amplifier tube, each cathode connected directly with the earthing point by additional earthing condensers, the cathode of each amplifier stage connected with the cathode of the following amplifier stage by a high-frequency choke, the impedance of said choke being purely inductive for the frequency to be amplified, and large as compared with the earthing resistance of 10 said earthing condenser, said anode-circuit filters containing additional small ohmic resistance for suppressing ultra-high-frequency oscillations, said small ohmic resistance connected directly with the anode cap, screening means for the 15 anode lead commencing after said insulating tube, said resistance being surrounded by an insulating tube.
5. In an amplifier system with several amplifier stages for obtaining very high amplifications, preferably for amplifying the intermediate frequency band of a television superheterodyne arrangement each of said amplifying stages containing an amplifier tube connected with an anode circuit, a screen grid circuit and a control 20 grid circuit, separate high-frequency filters in said anode-circuit, in said screen-grid-circuit and in said control-grid-circuit of each of said amplifier stages for avoiding disturbing coupling, said filters containing decoupling condensers connected directly with the cathode of the corresponding amplifier tube, each cathode connected directly with the earthing point by additional earthing condensers, the cathode of each amplifier stage connected with the cathode of the following amplifier stage by a high-frequency choke, the impedance of said choke being purely inductive for the frequency to be amplified and large as compared with the earthing resistance of 25 said earthing condenser, all heating leads of said amplifier stages connected with each other over high-frequency chokes, the impedance of which is purely inductive for the frequency to be amplified and large as compared with the earthing resistance of said earthing condenser, each of said heating leads associated with the single 30 tubes being connected to earth by a separate earthing condenser.
7. In an amplifier system with several amplifier stages for obtaining very high amplifications, preferably for amplifying the intermediate frequency band of a television superheterodyne arrangement including an oscillating stage with associated amplifier stages each of said amplifying stages containing an amplifier tube connected with an anode circuit, a screen grid circuit and a control grid circuit, separate high-frequency filters in said anode-circuit, in said screen-grid-circuit and in said control-grid-circuit of each of said amplifier stages for avoiding disturbing coupling, said filters containing decoupling condensers connected directly with the cathode of the corresponding amplifier tube, each cathode connected directly with the earthing point by additional earthing condensers, the cathode of each amplifier stage connected with the cathode of the following amplifier stage by a high-frequency choke, the impedance of said choke being purely inductive for the frequency to be amplified and large as compared with the earthing resistance of 35 said earthing condenser, the heating leads of the oscillating stage being connected with the heating leads of the following amplifier stage by high-frequency chokes, the heating leads of the associated amplifier stages being also connected with each other by high-frequency chokes but so that only between each second amplifier 40 stage high frequency chokes are arranged, said chokes being purely inductive for the frequency to be amplified and large as compared with the earthing resistance of said earthing condenser.
- 50 6. In an amplifier system with several amplifier stages for obtaining very high amplifications, preferably for amplifying the intermediate frequency band of a television superheterodyne arrangement each of said amplifying stages containing an amplifier tube connected with an anode circuit, a screen grid circuit and a control grid circuit, separate high-frequency filters in

KURT SCHLESINGER.
